PRECISION SICKLE SHARPENER

Floyd H. Shadle, Minatare, Nebr.

Application June 4, 1947; Serial 752,381

29 Claims. (Cl. 51—56)

1

This invention relates to novel and useful improvements in devices for treating, preferably sharpening, tools.

An object of this invention is to provide a stand having an improved support means thereon for a sickle bar and means for actuating said support means in a predetermined stepped sequence.

Another object of this invention is to provide means on said stand for grinding or otherwise sharpening the selected cutting edges of a sickle bar.

A further purpose of this invention is to provide means for resiliently biasing the cutter means in a predetermined selected direction.

A further purpose of this invention is to provide means for pivotally adjusting the cutter means for the purpose of treating opposed surfaces of the conventional sickle bar teeth.

Another object of this invention resides in the provision of means for selectively raising and lowering the cutting means at predetermined intervals during the cycle of operation of the invention.

Still another purpose of this invention resides in the pivoted nature of the said sickle bar support means, whereby opposed and oppositely inclined teeth surfaces of a conventional sickle bar may be readily and easily treated.

Another object of this invention is to provide means for retaining the sickle bar support means and means for retaining the cutting or grinding means in selected adjusted positions.

Other objects and features of novelty shall become apparent to those skilled in the art, in following the description of the preferred embodiment of the present invention, illustrated in the accompanying drawings, wherein:

Figure 1 is an elevational side view of the preferred embodiment of the present invention;

Figure 2 is a plan view of the invention disclosed in Figure 1;

Figure 3 is an elevational front view of the invention disclosed in Figure 1;

Figure 4 is an enlarged elevational view disclosing details of the adjustable and pivoted cutting means;

Figure 5 is an enlarged elevational view of a clamp utilized in conjunction with the present invention, and;

Figure 6 is a transverse sectional view of the longitudinal sickle retaining member taken substantially on the line 6—6 of Figure 2 and in the direction of the arrows.

Referring now in detail to the illustrated preferred embodiment of the present invention, like

2

reference characters are used throughout to indicate similar elements thereof.

The general purpose of the present invention as set forth in the objects thereof may be summed up as follows: a sickle bar is retained in a specially provided member and an index bar is clamped securely thereon. The sickle bar retaining member is pivoted to a stand, the travel of the said sickle bar retaining means being preferably about 60°. Means is provided for moving the index bar and consequently the sickle bar in stepped sequence after certain treating operations are performed on the teeth of the said bar. In performing the said treating operations, a cutting device is provided on a carriage which is slidable on tracks. These tracks form a portion of the stand. The cutting means is provided in a housing and the said housing is pivotally mounted, capable of a predetermined pivotal arc of rotation. Also, means for selectively raising and lowering the cutting means is provided in order that the cutting means will engage the selected teeth surfaces only at predetermined times. Of course, power means is provided for rotating the cutter means.

20 A stand, generally indicated by the reference numeral 10, is provided with several cantilever extensions forming a portion of the present invention. An appropriate base 12 is provided of any suitable material, such as angle iron or the like. A table 14 is suitably secured to and forms a part of the said stand 10. Means for retaining a sickle bar is pivoted to the said table 14 by any suitable means such as a bolt or pivot pin 16. A bracket 18 extends over the upper portion of the said table 14 and is also pivoted by utility of the said pivot pin 16. The said sickle bar retaining means comprises a discontinuous member 20 having a cut away portion at substantially the longitudinal center thereof. The said discontinuous member is composed of a pair of substantially identical base portions connected by means of tie rods 22. If desired, additional strengthening members may be supplied longitudinally of said sickle bar retaining means 20 such as angle iron braces 24. A conventional sickle bar 26 is received in an index bar 28 which is situated and guided in the said member 20. This bar 28 is L-shaped in cross section, including a horizontal leg which rests on the member 20 and a vertical leg. The said index bar 28 is provided with a plurality of slots 30 along the longitudinal axis thereof and on the top of the vertical leg for a purpose to be set forth in the subsequent portion of the specification. Support braces 32 extend from the said

member 20 to the base 12, whereon said support members 32 are pivoted. Any conventional pivot means may be used such as the bolts 34 disclosed in Figure 3. A slot 36 is received in one end of the said index bar 28 for the purpose of receiving the enlargement 38 therethrough, conventionally found in sickle bars. The said slot 36 permits of flexibility in that various size sickle bars may be utilized in the present invention and still be accommodated in the aperture formed by the said slot 36. In accordance with the flexibility of the said slot construction 36, a specially designed clamp has been devised for employment therewith. The usual ball joint 40 extending from the said sickle bar 26 is received in suitable receiving means. The preferable receiving means consists of a pair of circular apertured members 42 which engage the said ball joint member 40. Arms 45 having slots 46 therein extend from the said circular engaging members 42. These arms are fixedly secured to a perch 48 extending from the said index bar 28. A screw 50 extends through the said slot 46 and a wing nut, or a conventional equivalent, is engageable with the threads of the screw 50. This wing nut 52 is obviously employed in conjunction with the screw for the purpose of retaining the arms 45 and consequently the retaining means 42 against the said ball joint member 40. A second screw 50 and wing nut construction 52 is employed adjacent the circular retaining means 42 to further assure rigid clamping action.

Viewing Figure 2, there is disclosed a resilient clip 54 which is fixed to the said index bar 28 by means of a conventional screw construction. This resilient clip 54 is conventional in structure and is utilized for the purpose of retaining the sickle bar 26 in fixed position relative to the index bar 28. It is seen that by fastening the said resilient clip 54 to the said index bar 28 the sickle bar will be carried entirely by the index bar 28.

The said member 20 has been described as pivoted to and above the table 14. It is noted that the said pivot pin 16 and pivot 34 are on the same vertical axis, thereby allowing pivotal movement of the member 20. When the sickle bar retaining member 20 is positioned in one of its selected positions, assume that shown in Figure 2, means for assuring immovability is provided. This means consists of a link 58 pivoted to the undersurface of the said member 20, and having an aperture 60 adjacent the end thereof. This aperture is received on a pin 62 which may be resiliently biased from a housing 64, secured to a selected portion of the said table 14. The pin 62 and its associated housing 64 along with the resilient biasing means therein is conventional in nature being well known in many arts. Of course, when the sickle bar retaining means 20 assumes a position as shown in phantom in Figure 2, a second link 58, aperture 60 and pin 62 is utilized for retaining the said member 20 in the desired selected position. The purpose in providing the sickle bar pivoted construction is in order to sharpen all sides of the teeth, pertinent to conventional sickle bars.

A crank 66 is secured to a shaft 68 which is journaled in the said bracket 18. There is also provided a spring 70 for the purpose of biasing the crank outwardly relatively to the depending portion of the said bracket 18. This spring is preferably interposed between the crank 66 and the said depending portion of the member 18. A link 72 is secured to the inward terminal portion

of the shaft 68 and a pawl 74 is pivoted thereto. This pawl 74 engages the aforementioned slots 30 which are in selected spaced positions along the longitudinal axis of the index bar 28. Obviously, the handle 66 may be rotated in reversing the action thereby moving the index bar and consequently the sickle bar 26 predetermined selected amounts. Of course, these amounts correspond with the distance between teeth. Also, it is noted that the pawl 74 may be turned to a position opposite that shown in Figure 3 and the index bar 28 consequently reversed in its direction of movement.

Upon rotation of the crank 66, the pawl 74 resting on the vertical leg of the index bar 28 is slid an amount corresponding to the size of the crank throw. Further, the movement of the pawl, due to its pivotal connection with the crank mechanism, will be sliding movement on the bar 28. By engagement of the pawl in the successive slots upon rotation of the crank, the bar 28 is moved progressively.

A pair of tracks 78 and 80 respectively are secured to the said stand 10 by any suitable means, preferably by utility of a plate 82 extending across said stand 10. Of course, the tracks 78 and 80 may be secured thereto by any suitable conventional means such as bolts and the like. A carriage is slidably received on the said rails 78 and 80. This carriage carries a means for treating the teeth of a conventional sickle bar in order to sharpen or otherwise adjust the same. The said carriage consists of a pair of substantially parallel members 84 and 86 respectively connected by suitable cross members 88 and 90 respectively. The member 90 is preferably a wooden block having suitable apertures adjacent the extremities thereof for receiving the said parallel track members 78 and 80 respectively therethrough. The member 88 may extend across said tracks 78 and 80 and engage the same forming a bearing surface. A second block 92 is secured to the said block 90 and a guard 94 depends therefrom. Straps 96 may be employed in a conventional manner to retain the guards in the selected, desired position movable with the said carriage.

A bracket 98 is received on the front portion of the said blocks 90 and 92 and a cross member 100 extends substantially perpendicular thereto.

Means for pivotally and adjustably retaining a cutting element is provided in association with the carriage and more specifically the last mentioned bracket 98. For a detail of this construction, reference is made to Figure 4. Slotted and apertured members 102 and 104 respectively are adjustably received on the said cross member 100 by means of a conventional bolt 106 extending through the slots in the said slotted member. A housing 108 is provided with a right angular extension 110, which extends through a suitable aperture in the said block 92 and a suitable aperture in the brace or bracket member 98. This construction obviously permits of pivotal movement about the right angular extension 110 as an axis. A sleeve like housing 112 is received in a suitable bore provided in the said housing 108 and antifriction bearings 114 are provided at each end of the said sleeve like member 112. A cap 116 is provided on the upper portion of the said member 112 for the purpose of retaining the anti-friction bearing 114 in the desired relative position and for a purpose to be subsequently set forth. A shaft 118 is received through the said sleeve

like member 112 and a conventional thrust bearing, adjustable in nature, is supplied on the said shaft 118. This thrust bearing 120 is preferably in the form of a collar having a suitable set screw therein. The lower portion of the shaft 118 carries a conventional grinding stone or other abrading means 122. Washers 124 and 126 respectively may be utilized as well as the screw 128 in retaining the said abrading means 122 fixed to the said shaft 118 yet permitting of replacement when so desired. The opposite end of the said shaft 118 has an anti-friction bearing 130 associated therewith and a cage 132 journaled thereon. Brackets 134 extend from the cage 132 and a handle member 136 is pivoted thereto. This handle member has a rod 138 pivoted to a selected end, which rod terminates in immovable fixed relation on the said housing 108. Any suitable securing means may be utilized as welding, brazing or the like. The cap 116 has an extension 140 projecting therefrom and a shaft 142 secured thereto. This shaft is received in a suitable bore in the housing 108 and a resilient biasing means, preferably a spring, is interposed between the extension 140 and a selected portion of the housing 108. It may be seen now that upon actuation of the handle member 136, the inner sleeve like housing 112 will be projected upwardly or downwardly in accordance with the movement of the said handle member 136. Also, the resilient biasing means, or spring 143 urges the stone or abrading means 122 in a selected, predetermined direction. An arm 145 is secured to the terminal portion of the said extension 110 by any suitable conventional means such as the nut 146 cooperating with threads on the said extension 110. Obviously, a washer may be interposed between the arm 145 and the plate 98 to assist in smoothness of operation. The housing 150 may be secured to or formed integral with the said arm 145 and a spring loaded pin 152 supplied therein. This spring loaded pin is adapted to engage selected apertures in the said apertured arms 102 and 104 respectively. It may be readily appreciated that the said abrading means 122 along with its associated mechanism may be positioned selectively about adjusted pivoted positions considering the axis of the extension 110 as an axis of rotation.

From the construction of the structure described above, it may now be readily appreciated further that selected surfaces of the teeth of a conventional sickle bar may be treated independently. Further, the sickle bar teeth may be treated from two positions, that is while the bar is moving in either direction parallel to the longitudinal axis thereof.

The power supply means may be secured to or positioned adjacent the stand 10. The preferable source of power is a conventional motor 160 having a suitable bracket 162 for retaining the same in the desired fixed position. A pulley and belt construction may be employed for motivating the said abrading means 122. The shaft 164 is secured to and extends from the said stand 10 and a support means or pair of brackets 166 extends from the said base 12. The said shaft 164 may be detachably secured to the said stand 10 by utility of the plate 168 and bolt construction 172 as disclosed in Figure 1. A pulley cluster 174 is employed for attaining selected speeds of rotation of the said shaft 118. This cluster may be keyed or otherwise slidably secured to the shaft 164. Conventional pulley and belt construction 176

may be utilized as a power take off connecting the said shaft 164 drivingly with the said motor 160. Brackets 178 extend from the said parallel rails 86 and 84 respectively and a shaft 180 extends thereacross. Conventional pulleys 182 are journaled thereon and this construction serves the purpose of an idler. A final pulley 186 is fixedly secured to the said shaft 118 for the purpose of receiving a belt 188 therearound. This belt also extends over the said pulleys 182 and finally about a selected pulley in the said cluster 174. It may be seen that upon movement of the carriage, the said cluster 174 which is keyed or otherwise equivalently secured to the shaft 164 will be capable of sliding about the longitudinal axis of said shaft. Means for actuating this carriage longitudinally of the said tracks 78 and 80 respectively is provided. This means consists of an extension 192 rigidly secured to a selected track 78 and an operating lever 194 pivoted thereto. A pitman 196 is secured to a selected terminal portion of the said lever 194 and to a bracket 198 which is fixedly received on the said block 90. It is readily apparent that upon pivotal movement of the said actuating lever 194 the carriage will be moved longitudinally of the tracks 78 and 80. Also, means for resiliently retaining the said carriage is provided. This means consists of an arm 199 rigidly fixed to a selected track 84 and depending therefrom. A pitman 200 is secured to the said depending arm 199 and a spring or other suitable equivalent, 202 is received at the other end of the said pitman 200. The opposite portion of the spring 202 is anchored to a selected portion of the said rod or track 78 by any suitable means such as a small bracket and screw construction 204.

While there has been described and illustrated but a single preferred embodiment of the present invention, capable of performing all of the specifically mentioned objects, as well as numerous ancillary objects, it is apparent to those skilled in the art that various changes including omissions and additions may be made herein without departing from the spirit of the invention. Accordingly, limitation is sought only in accordance with the scope of the following claims.

Having described the invention, what is claimed

50 as new is:

1. A tool grinding device comprising a stand having tracks thereon, a carriage on said tracks, means pivoted to said carriage and to one of said tracks for moving said carriage longitudinally of said tracks, cutting means, means mounted on said carriage pivotally supporting said cutting means, means attached to said carriage for retaining said cutting means in selected pivotal positions, means pivoted to said carriage and said cutting means for raising and lowering said cutting means, means secured to said stand beneath said cutting means for supporting a work piece, means rotatably secured to said support for actuating said work piece support means in stepped sequence.

2. A tool grinding device comprising a stand having tracks thereon, a carriage on said tracks, means pivoted to said carriage and one of said tracks for moving said carriage longitudinally of said tracks, cutting means, means mounted on said carriage pivotally supporting said cutting means thereon, means attached to said carriage for retaining said cutting means in selected pivotal positions, means pivoted to said carriage

and said cutting means for raising and lowering said cutting means, means secured to said stand beneath said cutting means for supporting a work piece, means secured to said support for actuating said work piece support means in stepped sequence, said work piece supporting means including a longitudinal member pivoted to said stand and movable in a plane parallel to the plane of said tracks, an index bar, means for detachably securing a work piece to the index bar, and means mounted on said index bar for resiliently biasing the work piece to said longitudinal member.

3. A tool grinding device comprising a stand having parallel tracks thereon, a carriage on said tracks, means pivoted to said carriage and one of said tracks for moving said carriage longitudinally of said tracks, cutting means, means mounted on said carriage pivotally supporting said cutting means, means attached to said carriage for retaining said cutting means in selected pivoted positions, means pivoted to said carriage and said cutting means for raising and lowering said cutting means, means secured to said stand beneath said cutting means for supporting a work piece, means rotatively secured to said support for actuating said work piece support means in stepped sequence, said work piece supporting means including a longitudinal member pivoted to said stand, an index bar, means for detachably securing a work piece to the index bar, means for resiliently urging a work piece against said longitudinal member, said work piece support actuating means including a shaft journaled in said stand and having a pawl pivoted thereto, slots in said index bar selectively and progressively engaged by said pawl upon rotative movement of said shaft.

4. A tool grinding device comprising a stand having tracks thereon, a carriage on said tracks, means pivoted to said carriage and one of said tracks for moving said carriage longitudinally of said tracks, cutting means, means mounted on said carriage pivotally supporting said cutting means, means attached to said carriage for retaining said cutting means in selected pivotal positions, means pivoted to said carriage and said cutting means for raising and lowering said cutting means, means secured to said stand beneath said cutting means for supporting a work piece, means rotatively secured to said support for actuating said work piece support means in stepped sequence, said work piece supporting means including a longitudinal member pivoted to said stand for movement in a plane parallel to said tracks, an index bar, means for detachably securing a work piece to the index bar, means for resiliently biasing the work piece against said longitudinal member, said work piece support actuating means including a shaft journaled in said stand, a pawl pivoted to said shaft, slots in said index bar selectively and progressively engaged by said pawl, a handle for actuating said shaft, said carriage moving means including a lever pivoted to said tracks, means pivotally connecting said lever to said carriage and means for resiliently biasing said carriage longitudinally of said tracks.

5. The structure recited in claim 4 wherein said resilient carriage biasing means comprises a spring secured to one of said tracks and to said carriage.

6. A tool grinding device comprising a stand

having tracks thereon, a carriage on said tracks, a lever pivoted to said stand and said carriage for moving said carriage longitudinally of said tracks, cutting means, a pin positioned in said carriage and secured to said cutting means for pivotally supporting said cutting means for swinging movement in a plane normal to said tracks, means attached to said cutting means and said carriage for retaining said cutting means in selected adjusted positions, means for raising and lowering said cutting means, means on said stand beneath said cutting means for supporting a work piece, means supported by said stand for actuating said work piece support means in stepped sequence, said work piece supporting means including a longitudinal member pivoted to said stand, an index bar, means detachably securing said index bar to the work piece, means for resiliently clamping a work piece to said index bar, means attached to said stand for locking said longitudinal member in selected pivoted positions.

7. In a tool grinding device, a stand having a pair of parallel tracks thereon, a table mounted beneath said tracks, a carriage slidably supported on said tracks, means attached to said carriage by a pivotal connection for sliding said carriage in a single direction on said tracks, resilient means attached to said carriage and one of said tracks for returning said carriage, a grinding member, means mounting said grinding member on said carriage for movement transverse to the movement of said carriage and toward said table, means on said table for supporting a work piece beneath said grinding member, said means including an index bar having spaced slots therein, said work supporting means being pivotally associated with said table, and means movable pivotally with said work supporting means and engaging said slots for moving said index bar in a plane substantially parallel to the plane of said tracks.

8. In a tool grinding apparatus, a stand which includes a pair of tracks and a table positioned substantially parallel to and below said tracks, a carriage slidably supported on said tracks, a housing, means substantially parallel to said tracks and journaled in said carriage pivotally mounting said housing on said carriage, an axially movable shaft mounted in said housing, a cutting member supported at one end of said axially movable shaft, means for axially actuating said shaft attached thereto by a pivotal connection, means for supporting a work piece pivotally attached to said table and substantially parallel to said tracks, said work piece supporting means including an index bar, and means pivotally movable with said work supporting means for actuating said index bar in a plane substantially parallel to said tracks.

9. The combination of claim 8 and a latch secured to said table and engaging said work support means for retaining said work support means in a preselected pivoted position.

10. The combination of claim 9 and said work support means including a resilient member adapted to engage the upper surface of a work piece to resiliently urge the work piece to a fixed position on said work support means.

11. In a tool grinding apparatus, a stand which includes a pair of tracks and a table positioned substantially parallel to and below said tracks, a carriage slidably supported on said tracks, a housing, means substantially parallel to said tracks and journaled in said carriage pivotally mounting said housing on said carriage, an axially movable shaft mounted in said housing,

a cutting member carried on one end of said axially movable shaft, means for axially actuating said shaft attached thereto by a pivotal connection, means for supporting a work piece pivotally attached to said table and substantially parallel to said tracks, said work piece supporting means including an index bar, and means pivotally movable with said work supporting means for actuating said index bar in a plane substantially parallel to said tracks, a spring attached to said carriage and to one of said tracks for constantly biasing said carriage longitudinally of said tracks, means pivotally attached to said carriage and to one of said tracks for urging said carriage in a direction opposite the urging force of said spring.

12. In a grinding apparatus, a stand having parallel tracks and a carriage positioned thereon, means pivoted to said carriage and to one of said tracks for moving said carriage in one direction on said tracks, resilient means reacting on said carriage and at least one of said tracks for returning said carriage, grinding means, means carried by said carriage supporting said grinding means, a table secured to said stand beneath said tracks, a longitudinal member pivoted to said table and in a plane parallel to said rails, means slidably positioned on said member for supporting a work piece.

13. In a grinding apparatus, a stand having parallel tracks and a carriage positioned thereon, means pivoted to said carriage and to one of said tracks for moving said carriage in one direction on said tracks, resilient means reacting on said carriage and at least one of said tracks for returning said carriage, grinding means, means carried by said carriage supporting said grinding means, a table secured to said stand beneath said tracks, a longitudinal member pivoted to said table in a plane parallel to said rails, means slidably positioned on said member for supporting a work piece, said grinding means including a housing having an axially slidably shaft secured thereto, and means pivoted to said shaft and said housing for axially moving said shaft.

14. In a grinding apparatus, a stand having parallel tracks and a carriage positioned thereon, means pivoted to said carriage and to one of said tracks for moving said carriage in one direction on said tracks, resilient means reacting on said carriage and at least one of said tracks for returning said carriage, grinding means, means carried by said carriage supporting said grinding means, a table secured to said stand beneath said tracks, a longitudinal member pivoted to said table and in a plane parallel to said rails, means slidably positioned on said member for supporting a work piece, said grinding means including a housing with a grinding member supporting shaft therein, and said grinding means supporting means comprising a pivot pin attached to said housing and mounted on said carriage and extending parallel to said tracks.

15. In a grinding apparatus, a stand having parallel tracks and a carriage positioned thereon, means pivoted to said carriage and to one of said tracks for moving said carriage in one direction on said tracks, resilient means reacting on said carriage and at least one of said tracks for returning said carriage, grinding means, means carried by said carriage supporting said grinding means, a table secured to said stand beneath said tracks, a longitudinal member pivoted to said table and in a plane parallel to said rails, means slidably positioned on said member for supporting a work piece, said grinding means in-

cluding a housing with a grinding member supporting shaft therein, and said grinding means supporting means comprising a pivot pin attached to said housing and mounted on said carriage and extending parallel to said tracks, an arm secured to said pivot pin and movable therewith, a latch secured to said arm lockingly engaging said carriage to retain said abrading means in selected pivotal positions.

16. In a grinding apparatus, a stand having parallel tracks and a carriage positioned thereon, means pivoted to said carriage and to one of said tracks for moving said carriage in one direction on said tracks, resilient means reacting on said carriage and at least one of said tracks for returning said carriage, grinding means, means carried by said carriage supporting said grinding means, a table secured to said stand beneath said tracks, a longitudinal member pivoted to said table and in a plane parallel to said rails, a work supporting index bar mounted for sliding movement on said longitudinal member, and means movable pivotally with said longitudinal member for moving said index bar in step-by-step relation.

17. In a grinding apparatus, a stand having parallel tracks and a carriage positioned thereon, means pivoted to said carriage and to one of said tracks for moving said carriage in one direction on said tracks, resilient means reacting on said carriage and at least one of said tracks for returning said carriage, grinding means, means carried by said carriage supporting said grinding means, a table secured to said stand beneath said tracks, a longitudinal member pivoted to said table and in a plane parallel to said rails, a work supporting index bar mounted for sliding movement on said longitudinal member, and means movable pivotally with said longitudinal member for moving said index bar in step-by-step relation, said index bar being L-shaped adapted to seat a work piece on the horizontal leg thereof, and the vertical leg thereof having spaced slots therein progressively engaged by said index bar moving means.

18. The combination of claim 17 and said index bar moving means including a crank having a pawl pivotally mounted at one end thereof and resting on the vertical leg of said index bar.

19. The combination of claim 17 and latches attached to said table lockingly engageable with said longitudinal member to retain said member in a preselected pivoted position.

20. The combination of claim 17 and resiliently biased means secured to said longitudinal member and juxtaposed relative to the horizontal leg of said index bar to urge a work piece against the horizontal leg of said index bar.

21. In a grinding apparatus, a stand having parallel tracks and a carriage positioned thereon, means pivoted to said carriage and to one of said tracks for moving said carriage in one direction on said tracks, resilient means reacting on said carriage and at least one of said tracks for returning said carriage, grinding means, means carried by said carriage supporting said grinding means, a table secured to said stand beneath said tracks, a longitudinal member pivoted to said table and in a plane parallel to said rails, means slidably positioned on said member for supporting a work piece, said grinding means including a housing having an axially slidably shaft secured thereto, and means pivoted to said shaft and said housing for axially moving said shaft, and a spring reacting on said housing and

said shaft to resiliently return said shaft after axial movement of said shaft by the aforementioned means.

22. In a grinding apparatus, a stand having parallel tracks and a carriage positioned thereon, means pivoted to said carriage and to one of said tracks for moving said carriage in one direction on said tracks, resilient means reacting on said carriage and at least one of said tracks for returning said carriage, grinding means, means carried by said carriage supporting said grinding means, a table secured to said stand beneath said tracks, a longitudinal member pivoted to said table and in a plane parallel to said rails, means slidably positioned on said member for supporting a work piece, said grinding means including a housing having an axially slidable shaft secured thereto, and means pivoted to said shaft and said housing for axially moving said shaft, and a spring reacting on said housing and said shaft to resiliently return said shaft after axial movement of said shaft by the aforementioned means, which includes a link pivoted to said housing and said shaft.

23. A device for grinding a toothed work piece comprising a stand having a pair of tracks at the top portion thereof, a horizontal table positioned beneath said tracks and substantially parallel to said tracks, a longitudinal member pivoted to said table and movable in a plane substantially parallel to said tracks, an index bar slidably received on said longitudinal member and movable substantially parallel thereto, means pivotally movable with said longitudinal member for moving said index bar in step-by-step relation on said longitudinal member, resilient means attached to said longitudinal member for urging a work piece against said index bar, a latch attached to said table and engaging said member to retain said member in a predetermined pivotal position, a live shaft attached to said stand and having a pulley axially slidably thereon, a carriage slidably supported on said tracks, a countershaft journalled on said carriage having a pulley thereon, grinding means including a housing and an axially slidable shaft therein adapted to retain a grinding element at one end thereof, a pivot pin attached to said housing and mounted in said carriage attaching said grinding means to said carriage for movement therewith, said last mentioned shaft having a pulley thereon and a flexible driving element entrained about said first mentioned, second mentioned and last mentioned pulleys to transmit rotative movement from said live shaft to said axially movable shaft, and manually operative means attached to said housing and pivotally secured to said axially movable shaft for raising and lowering said shaft.

24. A device for grinding a toothed work piece comprising a stand having a pair of tracks at the top portion thereof, a horizontal table positioned beneath said tracks and substantially parallel to said tracks, a longitudinal member pivoted to said table and movable in a plane substantially parallel to said tracks, an index bar slidably received on said longitudinal member and movable substantially parallel thereto, means pivotally movable with said longitudinal member for moving said index bar in step-by-step relation on said longitudinal member, resilient means attached to said longitudinal member for urging a work piece against said index bar, a latch attached to said table and engaging said member to retain said member in a predetermined pivotal position, a live shaft attached

to said stand and having a pulley axially slidable thereon, a carriage slidably supported on said tracks, a countershaft journalled on said carriage having a pulley thereon, grinding means including a housing and an axially slidable shaft therein adapted to retain a grinding element at one end thereof, a pivot pin attached to said housing and mounted in said carriage attaching said grinding means to said carriage for movement therewith, said last mentioned shaft having a pulley thereon and a flexible driving element entrained about said first mentioned, second mentioned and last mentioned pulleys to transmit rotative movement from said live shaft to said axially movable shaft, and manually operative means attached to said housing and pivotally secured to said axially movable shaft for raising and lowering said shaft, an arm attached to said pivot pin and means secured to said arm engaging said carriage for retaining said housing in selected pivoted positions.

25. A device for grinding a toothed work piece comprising a stand having a pair of tracks at the top portion thereof, a horizontal table positioned beneath said tracks and substantially parallel to said tracks, a longitudinal member pivoted to said table and movable in a plane substantially parallel to said tracks, an index bar slidably received on said longitudinal member and movable substantially parallel thereto, means pivotally movable with said longitudinal member for moving said index bar in step-by-step relation on said longitudinal member, resilient means attached to said longitudinal member for urging a work piece against said index bar, a latch attached to said table and engaging said member to retain said member in a predetermined pivotal position, a live shaft attached to said stand and having a pulley axially slidably thereon, a carriage slidably supported on said tracks, a countershaft journalled on said carriage having a pulley thereon, grinding means including a housing and an axially slidable shaft therein adapted to retain a grinding element at one end thereof, a pivot pin attached to said housing and mounted in said carriage attaching said grinding means to said carriage for movement therewith, said last mentioned shaft having a pulley thereon and a flexible driving element entrained about said first mentioned, second mentioned and last mentioned pulleys to transmit rotative movement from said live shaft to said axially movable shaft, and manually operative means attached to said housing and pivotally secured to said axially movable shaft for raising and lowering said shaft, a link secured to said carriage and pivoted to one of said tracks for axially sliding said carriage on said rails.

26. The combination of claim 25 and a spring seated on said housing and reacting on said slidable shaft constantly urging said shaft in a direction away from said table.

27. The combination of claim 25 and a spring seated on said housing and reacting on said slidable shaft constantly urging said shaft in a direction away from said table.

28. A tool grinding device comprising a stand having tracks thereon, a carriage disposed on said tracks, means pivoted to said carriage and one of said tracks for moving said carriage longitudinally of said tracks, a shaft, means securing said shaft to said carriage for pivotal movement and for axial movement, cutting means fixed to said shaft, means for releasably locking said shaft in selected pivoted positions, means

13

for axially operating said shaft to raise and lower said cutting means, means disposed on said stand beneath said cutting means for supporting a work piece, and means carried by said stand for moving said work piece supporting means in stepped sequence.

29. A tool grinding device comprising a stand, tracks carried by said stand, a table carried by said stand below said tracks, a carriage movably disposed on said tracks and means pivoted to one 10 of said tracks for moving said carriage longitudinally on said tracks, a housing having a bore, means pivotally mounting said housing at one pair of ends of said tracks, a shaft mounted for axial movement in said bore toward and away 15 from said table and movable pivotally with said housing, a cutting means carried by said shaft, and means for releasably locking said shaft in selected pivoted positions, means operatively connected with said shaft for moving said shaft 20 axially thereby moving said cutting means to-

14

ward and away from said table, means carried by said table below said cutting means for supporting a work piece for pivotal movement in a plane substantially parallel to said tracks, and 5 carried by said stand for moving said work piece supporting means in a horizontal plane in stepped sequence.

FLOYD H. SHADLE.
